UNITED STATES PATENT OFFICE.

CLARENCE H. MORROW, OF CLEVELAND, OHIO, ASSIGNOR TO THE HOTSTREAM HEATER COMPANY, OF CLEVELAND, OHIO, A CORPORATION OF OHIO.

BURNER.

Application filed May 22, 1925. Serial No. 32,101.

This invention relates to side feed gas burners and more particularly to gas burners for use in connection with water heaters in which the water supply or circulating system includes a vertical pipe at the bottom of the heater around which the burner is located and must be assembled.

The object of the invention is to provide a burner of the kind described which is of simple construction and can be made at low cost; which is so arranged as to enable it to be readily attached to or removed from the heater without disturbing the water connections; which is firmly and rigidly supported when in use; and which properly distributes the gas jets over the horizontal area with proper provision for the supply of air to secure efficient combustion and maximum heating effects.

In the drawings, which represent one embodiment of the invention, Fig. 1 is a horizontal section on the line 1—1, Fig. 2; Fig. 2 is a sectional elevation on the line 2—2, Fig. 1, showing the burner applied to the lower portion of a water heater; Fig. 3 is an inverted plan view of the central portion of the burner; and Fig. 4 is a detail section, on a larger scale, on the line 4—4, Fig. 1.

Referring to the drawings, 1 indicates the casing or jacket of an ordinary gas burning water heater, said jacket being of any suitable construction with or without a door or doors, as desired. For convenience of illustration, it is shown as including a depending flange or skirt 2 provided with a plurality of lugs or ears 3 which serve as seats for the burner to be described. Within the chamber of said jacket, and through which chamber the heated products of combustion rise from the burner, is located the water container or heater, shown as a hollow member 4 with a vertically centrally disposed bottom water supply pipe 5, through which water flows into the container 4 to be discharged therefrom through the upper outlet pipe (not shown) as is usual.

The burner forming the subject matter of the present invention may be made of any suitable form, but is usually a single hollow member, such as a cored casting, provided at the proper or any desirable places with lugs or ears 6 adapted to rest upon the jacket seats 3 and to be secured thereto by bolts 7, if desired. One portion of the casting, marked 8, is of hollow tubular form and

serves as the lateral or side supply for the mixture of gas and air introduced into the usual valved Bunsen inlet 9. The burner as a whole, excepting for desirable or necessary unequal spacing of the lugs 6, as shown, is symmetrical about a vertical plane through the axis of the tubular mixture supply portion 8 and includes two oppositely disposed substantially semi-circular outer chambered portions 10 from which the lugs 6 extend, said outer semi-circular portions being connected by cored radially extending portions 11 to the base of a U-shaped portion 12, the arms or side members 12 of which are parallel and extend from the radial portions 11 to the ends of the semi-circular portions 10 and which arms between them form an open ended slot or recess 13 extending from the outside of the burner to its center and in alignment with the tubular portion 8. This slot enables the burner to be pushed into place from one side and properly assembled about the water pipe 5, so that the burner may be assembled with the jacket after the water connections have been made, or may be removed from the jacket for cleaning or replacement after installation.

When the burner is pushed home or to the position shown in Fig. 2, the pipe 5 rests against a plurality, two being shown, of pads or blocks 14 cast integrally with the burner and located near the base of the U portion 12. Opposite each of said pads and located on the bottom of each of the arms 12 of the U shaped portion 12 is an adjustable set screw 15, which set screws may be screwed home after the burner is assembled about the water pipe, as shown in Fig. 3, in order to clamp it firmly in position. Of course, the outer end of the mixture supply portion 8 is supported by the gas pipe which supplies gas to the burner mixture, as is usual. All portions of the burner, including the outer semi-circular portions 10, the radial portions 11 and the U shaped portion 12 are cored or chambered, the passages and chambers therein communicating with each other and with the chamber 16 in member 8. It will be observed that the mixture of gas and air is carried by member 8 practically to the center of the burner and then distributed by the shortest possible paths to all parts of the burner from which it issues in a plurality of jets through the perforated 1

teats 17 distributed uniformly over the upper surface of the burner. The arrangement of the several chambered portions of the burner supplies a series, four being shown, 5 of openings 18, which with the slot 13, break up the otherwise flat surface of the burner and enable air to be supplied between jets and thereby promote combustion. Each jet, in the burner shown, is closely contiguous 10 to an opening to the burner and through which air is supplied to said jet.

What I claim is:

1. A side gas burner for heaters of the type including a substantially vertical pipe, 15 comprising outer oppositely disposed substantially semi-circular chambered portions and a substantially U-shaped chambered portion spaced therefrom and connected thereto, said substantially U-shaped portion 20 having its arms spaced to form an open ended slot extending from one side of the burner to the central axis thereof for lateral assembly of the burner with the vertical pipe, and a mixture feeding portion having a passage 25 in communication with the chambers of said semi-circular and U-shaped portions.

2. A side feed gas burner for heaters of the type including a substantially vertical pipe, comprising outer oppositely disposed 30 substantially semi-circular chambered portions and a substantially U-shaped chambered portion spaced therefrom and connected thereto, said substantially U-shaped portion having its arms spaced to form an open 35 ended slot extending from one side of the burner to the central axis thereof for lateral assembly of the burner with the vertical pipe, and a mixture feeding portion having

a passage leading to the base of the chamber of said U-shaped portion and communicating also with the chambers of said substantially semi-circular portions. 40

3. A side feed gas burner for heaters of the type including a substantially vertical pipe, comprising outer oppositely disposed 45 substantially semi-circular chambered portions and a substantially U-shaped chambered portion connected thereto by radially extending chambered portions, said substantially U-shaped portion having its arms 50 spaced to form an open ended slot extending from one side of the burner to the central axis thereof for lateral assembly of the burner with the vertical pipe, and a horizontally extending mixture feeding portion 55 in alignment with said open ended slot and having a passage in communication with the chambers of said semi-circular portions, said radially extending portions and said U-shaped portion. 60

4. A side feed gas burner for heaters of the type including a substantially vertical pipe, comprising outer oppositely disposed substantially semi-circular chambered portions, a substantially U-shaped chambered 65 portion connected therewith and having an open ended slot for assembly of the burner with the vertical pipe, the base of said U-shaped portion being provided with projecting seats for said pipe, and a pair of opposed adjustable means on the lower side of 70 said burner located opposite said seats for clamping the burner to said pipe.

In testimony whereof I hereby affix my signature.

CLARENCE H. MORROW.
